(57) **CLAIM**

The ornamental design for threaded rings for a vessel, as shown and described.

DESCRIPTION

FIG. 1 is an isometric view of threaded rings for a vessel, showing our new design, shown in an assembled configuration;

FIG. 2 is a front view thereof;

FIG. 3 is a back view thereof;

FIG. 4 is a right-side view thereof;

FIG. 5 is a left side view thereof;

FIG. 6 is a top plan view thereof;

FIG. 7 is a bottom plan view thereof;

FIG. 8 is an exploded perspective view thereof, showing the rings in a disassembled configuration; and,

FIG. 9 is another exploded perspective view thereof, showing the threaded rings in a position of use with an exemplary vessel.

The broken lines shown in FIG. 9 represent environmental subject matter of an exemplary vessel and form no part of the claimed design.
